UNITED STATES PATENT OFFICE.

FRANCIS W. COOPER, OF MONTREAL, QUEBEC, CANADA, ASSIGNOR TO STEAD RAIL ANCHORS INCORPORATED, OF WILMINGTON, DELAWARE, A CORPORATION OF DELAWARE.

RAIL ANCHOR.

Application filed February 8, 1926. Serial No. 86,915.

This invention relates broadly to improvements in rail anchors, and more particularly to one-piece rail anchors.

The primary object of the invention is to provide a one-piece rail anchor which may be manufactured at low cost and very easily and quickly installed on rails without the use of special tools and which will be durable and efficient.

10 Another object is to provide a substantially symmetrical or double-ended anchor which will be reversible and will in consequence have at least double the life of a single-ended anchor.

15 A still further object is to provide an anchor capable of reversal to relieve certain localized stresses therein, thus giving the metal opportunity to recover from the fatigue effects of a constant stress.

20 Another object is to provide a rail anchor having very large bearing surface for abutment against a tie.

Still another object is to provide a one-piece rail anchor which will if either slewed 25 or canted from its normal relation to a rail, by pressure against a tie, increase its grip upon the rail.

Additional objects and the advantages of the invention may be ascertained from the 30 following description and the accompanying drawings.

Various forms of one-piece rail anchors have been proposed and several are in use. In general, these anchors each comprise a 35 body hooked at one end to embrace one flange of a rail base and differently formed at the opposite end to press against the edge of the other base flange. The opposite ends of such anchors being differently 40 formed, neither end will perform the functions of the other end. Usually the hooked ends of such anchors are more severely stressed than the other ends and, if the stress develops into a strain, the anchors lose 45 their grip on the rail and cannot, ordinarily, be retained in service.

According to the present invention, the anchor comprises a body carrying two substantially similar end portions for engagement respectively with the two flanges of a rail base, the said end portions being so formed that each end is capable of engaging a rail base flange in two entirely different

ways. If either end becomes fatigued and develops strain, the anchor may be reversed, 55 so that the unstrained end performs the functions of the strained end and vice versa. In greater detail, the anchor preferably comprises a bar of resilient material, such as 60 spring steel, bent at its ends to form mutually facing substantially similar hooks, each adapted to embrace one flange of a rail base from above and below and each having a portion designed for abutting relation with the edge and lower surface of a base 65 flange. When the anchor is forcibly applied to a rail base, one end is in embracing relation with one base flange and is much more severely stressed than the other end, which is in abutting relation with the edge and bottom of the other flange. If that end of the anchor which is embracing a rail base flange shows signs of fatigue, the anchor may be removed and reapplied with the end which formerly abutted the flange now in flange 70 75 embracing position, and vice versa. The arrangement is such that the stresses in the anchor incident to performance of the two functions are substantially opposite, so that an end strained in performance of one function is subjected to counteracting stress or relieved of all stress in performance of the other function. That end of the anchor in flange abutting position depends below the rail base and forms an abutment to engage 80 85 a tie.

In the accompanying drawings which illustrate certain embodiments of the invention, but to the details of any or all of which the invention is not confined in the broad 90 aspects thereof, the same being disclosed for illustration and not with limitative intent:—

Fig. 1 is a plan view of a rail anchor formed according to the present invention as seen in position on a rail.

Figs. 2, 3 and 4 are side elevations of various modifications of one type of anchor as seen in position on a rail and each being in plan substantially as shown in Figure 1.

Referring to the drawings, 11 and 12 designate the flanges of a rail base and 13 and 14 the substantially similar end hooks of a rail anchor shown as engaging the flanges 11 and 12 respectively, and connected by a shank 15 extending beneath the base at right angles to the line of rail length. As will

be seen, the hooks of the type of anchor herein dealt with are mutually facing and both formed on the same side of the shank, that type of anchor characterized by disposition 5 of the hooks on opposite sides of the shank being dealt with in a separate application.

The tip or point of each hook is formed on its inner and outer surfaces, that is, the surfaces respectively nearest to and farthest 10 from the shank, with preferably flat rail engaging portions or seats 16 and 17, respectively, the outer of which extend from the tips of the hooks to outwardly extending shoulders 18 substantially normal to such 15 seats, at which shoulders the seats terminate. The tip formation of the hooks is very conveniently produced by an upsetting operation, for instance in a bolt heading machine, but may be obtained by other 20 methods. The distance between the throat of either hook and the shoulder 18 of the other hook is not less than the width of the rail base for which the anchor is designed and is preferably slightly greater. The 25 seats 16 and 17 of each hook are preferably at a definite angle to one another, which angle is substantially twice the angle between the upper and lower surfaces of the rail base flange for which the anchor is designed. The seats 16 and 17 and the shoulders 18 of the two hooks are so related that, 30 when the anchor is in position on a rail, the inner seat 16 of either hook will rest flat on the upper surface of one base flange, 35 while the outer seat 17 and shoulder 18 of the other hook will rest flat against the under side and edge surface, respectively, of the other base flange.

The shank 15 is preferably bent at the 40 root of each hook in the opposite direction to the bend of the hook, the bend being most advantageously located opposite a point in the hook intermediate the tip and throat of the hook, as indicated at 45. These bends form on the inner side of the shank what may be described as inward 50 projections or projections into the openings of the hooks serving as bearing surfaces, and designated by the numeral 20, the openings of the hooks being thereby restricted so as to be of less width at the projections or bearing surfaces 20 than at either mouth or throat. This formation, while preferable 55 to provide for a suitably large radius to the bend of the hook, is not essential as to greater opening at the throat of the hook than opposite the projection 20, and may be departed from if necessary or desirable. It is, however, essential that the projection 60 20, adapted to bear on the under side of a rail base flange, should be in such relation to the inner seat 16 of the hook that the hook will embrace the flange very tightly, 65 preferably so tightly that when the hook is forced into position on the flange it (the

hook) will be slightly sprung open as indicated by comparison of the dotted and full lines of the hook 13, Figure 2, the dotted lines indicating the normal or relaxed form of the hook. It is also essential that the 70 projections 20 or equivalent bearing surfaces of the shank arms be so located on the arms that, when the anchor is in position on a rail, the surface 20 engaging the under side of the rail base will bear thereon not appreciably nearer the vertical central plane 75 of the rail than the overlying hook seat 16 engages the upper surface of the rail base. There may be an anchor surface engaging the rail bottom between the hook tip and the central plane, but in such case the bearing point is the point of contact nearest the flange edge. The effectiveness of tension in the opened hook to maintain the anchor in position depends upon the distance of the bearing surface 20 outwardly of bearing surface 16 and the effectiveness decreases as the surface 20 is shifted inwardly nearer to the surface 16, and vice versa.

The shank may take a variety of shapes, 90 which distinguish the modifications of the type of anchor shown in Figures 2, 3 and 4. The modification shown in Figure 2, in which the shank is outwardly bent, is in some respects preferable to the other modifications, in that it provides at maximum distance below a rail the maximum length 95 of surface to bear against a tie. The shank is shown with a central curved portion 21 and two substantially straight portions or 100 arms 22 extending between the central curved portion and the bends 19.

The angle between the arms 22 may be increased or decreased as desired, both conditions being indicated by broken lines in 105 Figure 2. Also the length of the central curved portion 21 may be increased as desired, even to the point of producing a continuous curve between the bends 19, as indicated, but with opposite curvature, in 110 Figure 4.

In Figure 3, the shank, now designated 115 15^a, is substantially straight between the bends 19, while in Figure 4 the shank, designated 15^b, is inwardly curved, the curvature being shown as continuous between the 120 hooks and locating the bearing surfaces 20 nearer the central plane of the rail than in Figures 2 or 3. Obviously, in this modification, distinguished by its inwardly bent shank, the curvature may be localized in the 125 centre of the shank producing a shank similar to that of Figure 2, but of course oppositely bent. The inwardly bent shank modification has the advantage over other 130 modifications of the same type that the tie abutment is concentrated as far as possible from the rail flange embracing end, thus obtaining the maximum slewing effect. Also, in this modification and in the straight shank 130

modification of Figure 3, the tie abutting portion of the shank crosses the grain of the tie and so develops to the maximum degree the resistance of the tie to anchor embed-
 5 ment, whereas in the modification of Figure 2 the arm 22 farthest below the rail is substantially parallel with the tie grain and may perhaps be more readily embedded in the tie than in the case of the modification
 10 shown in Figure 4. On the other hand, the modification of Figure 2 has greater length of tie bearing at the maximum distance below the rail but to offset this carries the bearing farther under the rail. The straight
 15 shank modification of Figure 3 is obviously a compromise. From all of the foregoing, it will be seen that each modification has its own inherent advantages and that, on general grounds, no one modification is prefer-
 20 able and that preference may be given only according to the service conditions under which the anchor will be required to function and also according to facility of manu-
 25 facture.
 The modification shown in Figure 4 ex-
 30 hibits among its other differentiating fea-
 tures a substantial absence of the clearly de-
 35 fined bend 19 of the other modifications but
 the bend is nevertheless present by reason of
 40 the continuous bend of the shank which takes
 the reverse direction to the hook bend and
 therefore complies with the specification of
 45 the bends 19.

The method of applying the anchor to a
 50 rail and removing the same from a rail is
 extremely simple. For application, the an-
 55 chor is passed under a rail, as tightly as pos-
 sible in contact with the tie against which it
 60 is intended to thrust, with one end hook
 (for example the hook 13) embracing one
 65 base flange of the rail and the other end hook
 (in this example the hook 14) underlying the
 other base flange. As the anchor is advanced
 70 under the rail, the seat 16 at the end of the
 hook 13 slides up on the inclined upper sur-
 75 face of the flange 11, so that the top of the
 projection 20 is drawn up into engagement
 80 with the under surface of the rail base and
 further advance of the anchor across the rail
 85 necessitates resort to considerable force to at-
 90tain to the service position illustrated, such
 force being usually applied by striking the
 95 outer end of the hook 13 with a hammer. In
 course of this forcibly effected advance of the
 100 anchor, the wedge-shaped rail base flange
 wedges between the tip of the hook (13)
 105 and the projection or bearing surface 20 and
 springs the hook slightly open and perhaps
 110 to a greater degree than shown in Figure 2.
 It will be noted that the seat 16 of the hook
 115 13 engages the base flange nearer the cen-
 tral vertical plane of the rail than the pro-
 120 jection or bearing surface 20. This causes
 125 the anchor to act as a lever, fulcrumed on
 130 the rail bottom at the projection or bearing

surface 20 and pressing upwardly at its end
 14 against the bottom of the rail. With an
 anchor of proper form, size, cross section
 and temper, this upward pressure of the
 15 hook will be very considerable. When the
 anchor has been sufficiently advanced, the
 shoulder 18 of the hook 14 passes the edge
 20 of the base flange 12 and, by reason of ten-
 sion in the anchor, the same swings about
 25 its fulcrum point to press the seat 17 of the
 hook 14 against the bottom of the rail base.
 This movement of the anchor partially re-
 lieves the hook 13 which contracts toward its
 30 normal shape, shown in dotted lines Figure
 2, as far as the position shown in full lines
 35 in the same figure. It will be understood
 that the degree of hook flexion is perhaps ex-
 40aggerated in the drawings, for purposes of
 clear illustration. Obviously the hook 13,
 45 and in fact the whole anchor, is still under
 50 considerable tension operating to thrust the
 55 seat 17 of the hook 14 upwardly against the
 60 bottom of the base flange 12. This upward
 65 pressure of the hook 14 holds the same
 70 against dropping away from the rail base
 75 and permitting the shoulder 18 to disengage
 80 the edge of the base flange 12. The shoul-
 85 der 18, in turn, holds the whole anchor
 90 against retreating movement due to the con-
 95 traction of the hook 13 upon the tapering
 base flange 11.

Removal of the anchor is very easily ac-
 100 complished by striking the hook 14 down-
 105 wardly and toward the rail, so as to drive
 the shoulder 18 out of engagement with the
 110 edge of the base flange 12 and under the
 flange. The anchor may then be easily
 115 driven off the rail by striking horizontally
 120 toward the rail on the outer end of the hook
 125 14, the removal being assisted by the contrac-
 130 tion of the hook 13 on the tapering base
 flange 11.

It will readily be seen that the hook 13
 135 will grip the flange 11 very tightly from
 above and below and also that, by reason of
 140 this grip on the tapering flange 11, the
 anchor will have enough retreating tendency
 to cause the shoulder 18 of the hook 14 to
 145 grip the edge of the flange 12 very tightly.
 Thus, the anchor grips the rail base in two
 150 directions, namely, vertically and hori-
 zontally. In addition, the upward pressure of
 155 the hook 14 produces some frictional grip
 between the seat 17 and the bottom of the
 160 flange 12. The total gripping effort of the
 anchor is such that considerable force must
 165 be exerted to move the same along the rail,
 the major portion of the gripping effort be-
 170 ing, however, concentrated in the hook 13.
 The anchor when properly applied lies
 175 transversely of a rail and in a plane at right
 angles to the bottom of the rail base, and
 the tendency of the gripping effort is to
 180 maintain the anchor in this relation to the
 rail.

While the major portion of rail gripping effort is exerted at the end 13 of the anchor, the maximum dependence of the anchor below the rail is at the opposite end 14, which feature is of great importance in the functioning of the anchor and advantage resides in locating the portion of maximum dependence, and resulting bearing against a tie, as far as possible from the flange embracing hook, as previously touched upon in discussion of the different modifications illustrated. When the anchor is thrust against a tie by reason of creeping tendency in a rail, the anchor has no bearing or practically no bearing against the tie at the flange embracing end, especially if a tie plate intervenes between the rail and tie as is now usually the case. The thrust is therefore nearly all at the opposite end of the anchor and tends to slew the anchor out of its normal position transversely of the rail. The thrust also tends to cant the anchor out of its normal plane. In the case of slewing, the anchor cannot elongate sufficiently to accommodate itself to the greater distance angularly across the rail and, therefore, the hook 13 must move inwardly on the base flange 11, thus materially increasing its grip and also the grip of the shoulder 18 of the hook 14 against the edge of the flange 12. The canting tendency is transmitted from the hook 14 to the hook 13 as a torsion stress in the shank, and serves to further increase the grip of the hook 13 on the base flange 11. The nearer the point of maximum pressure against a tie is brought to the hook 13, the shorter is the leverage through which the pressure acts on the hook and therefore the less the effect produced. If the point of pressure against a tie is brought directly under the hook 13, there will not be any slewing effect but only canting effect, and this may not be sufficient to enable the anchor to hold a rail against sliding through the anchor. The modification shown in Figure 4 therefore gives, in its type, the maximum increase of grip due to slewing while the modification of Figure 2 will have a greater bearing against a tie with perhaps less increase of rail grip due to slewing but more increase of rail grip due to canting. The bent shank modifications (Figures 2 and 4), on the other hand, will tend to elongate under slewing pressure, thus perhaps minimizing the slewing effect which is transmitted without appreciable diminution through the straight shank modification of Figure 3. While there may be slight loss in force transmission through the bent shanks, there is the great advantage of resiliency in the shanks, which resiliency serves to relieve both end hooks of stresses which might be detrimental, and also serves to assist in maintaining the grip of the anchor against loosening due to vibration or other causes.

It is apparent that the foregoing and other considerations must be carefully weighed in determining which modification is best suited for any given conditions of service and that no one modification can be, in a general statement, preferred to others.

It will be observed that when the modifications of anchor shown in Figures 2, 3 and 4 are in service, the hooks are subjected to oppositely acting stresses, that is, the hook 13 is resisting an opening pressure while the hook 14 is resisting a closing pressure. If, after long use, the metal of the flange embracing hook (13) should become fatigued and the hook lose its resiliency and grip on the rail base flange, or if the hook should be found either soft or hard due to defective tempering, the anchor may be reversed and the other hook (14) placed in the position of the first hook (13) and vice versa. An anchor thus reversed may continue to give efficient service for many years and it may even be found that, by reversal of the stress in the first hook (13), the metal will in time recuperate and be capable of further use in its original relation to a rail.

While the foregoing description infers manufacture of anchors of the various modifications discussed by bending the same from bars of metal rectangular in cross section, it is to be understood that the invention is not by any means confined to this method of manufacture or to material of the cross section shown, but contemplates use of metal of other cross sections and employment of other methods such as punching or shearing from flat bars or sheets, or even forging from billets or blanks, or any combination of these methods with one another or with other methods. It is, however, at the present time deemed preferable to employ the bending method since this presents no difficulties and enables the anchors to be quickly, easily and inexpensively produced without waste. The bending method has the further advantage that the anchors may be made easily of the thickness necessary to have any desired length of rail bearing surface, in the direction of rail length, a considerable length of bearing being essential to the attainment of increased flange grip as a result of canting tendency. While the anchor is illustrated as flat, and is preferably flat, it may be otherwise formed if desired. Furthermore, while the hooks are shown as exactly similar, it will be understood that this has reference to the relation of the bearing surfaces 16, 17, 18 and 20, or equivalents, and that the exact curvature of the hooks is more or less immaterial and may vary between the two hooks of an anchor. Also the number of seat surfaces 17 and shoulders 18 per hook may be increased if desired.

In addition to the advantages already discussed, it may be pointed out that the double

hook construction of all modifications is inherently resilient and capable of withstanding vibration without reduction in the tenacity of rail gripping action and without creeping on a rail and is, moreover, capable of contracting upon a rail to compensate for any wear which may occur. All modifications of this type of anchor are manifestly extremely sturdy and are of such design that improper application is literally impossible. In process of application, the flange embracing hook of each anchor is unavoidably tested and, if soft or otherwise defective or of too large a size for the rail, will exhibit its fault, thus enabling immediate remedy. A single size of anchor may be made to serve a considerable range of variations in rail base width and rail base thickness by merely varying the opening of the hooks, or by other means, alone or in combination with variation of hook opening. This feature, coupled with the extreme simplicity of design and the absence of waste, enables the anchors to be manufactured very easily and at small cost. The capacity for reversal and the obvious fact that the anchor is not injured by removal from a rail but is capable of re-use combine to render the anchor very economical. Other advantages will be apparent to those skilled in the manufacture and use of track equipment of this class.

Many variations of minor detail may be made without departing from the spirit of the invention and all variations, modifications, substitutions and changes, whatsoever, as fall within the scope of the appended claims are to be deemed as included in the invention.

Having thus described my invention, what I claim is:—

1. A rail anchor to extend under a rail, including a hook at each end, both of said hooks lying on the same side of the anchor and each hook being formed to engage a flange of the rail base in either of two ways.

2. A rail anchor to extend under a rail, including a hook at each end, both of said hooks lying on the same side of the anchor and each hook being formed to engage a flange of the rail base at either of two bearing surfaces spaced apart on the hook.

3. A rail anchor, to extend under a rail, including a hook at each end, the tip of each of said hooks being adapted at one time to engage only the upper surface of one flange of the rail base and at another time to simultaneously engage only the lower surface and edge surface of the same flange.

4. A rail anchor, to extend under a rail, including a hook at each end, one of said hooks being formed at the inner surface of its tip end to engage the upper surface of one flange of the rail base and the other of said hooks being formed at the outer surface of

its tip end to engage the lower surface and edge surface of the other flange, each of said hooks being additionally formed to engage a base flange in the manner specified for the other hook.

5. A rail anchor, to extend under a rail, including a hook at each end, each of said hooks being recessed or notched at the outer surface of its tip end and being also chamfered at the inner surface of its tip end.

6. A rail anchor, to extend under a rail, including a pair of substantially similar hooks, one at each end thereof, and in service adapted one to press down at its tip on one flange of the rail base and the other to press inwardly at its tip on the edge of the other flange.

7. A rail anchor, to extend under a rail, including a pair of substantially similar hooks, one at each end thereof, and in service adapted one to press down at its tip on one flange of the rail base and the other to press inwardly at its tip on the edge of the other flange, and simultaneously upwardly on the bottom of said other flange.

8. A rail anchor comprising a body and a hook at each end of the body, each hook being formed at the inner surface of its tip end to engage the upper surface of a rail base flange, and being further formed at the outer surface of its tip end to engage the under surface of a rail base flange.

9. A rail anchor comprising a body and a hook at each end of the body, each hook being formed at its tip end to engage the upper surface of a rail base flange, and being further formed at its tip end to engage the under and edge surfaces of a rail base flange, and an inward projection within each hook adapted to engage the under surface of a rail base flange.

10. A rail anchor comprising a body and a hook at each end of the body, each hook being formed at its tip end to engage the upper surface of a rail base flange, and being further formed at its tip end to engage the under and edge surfaces of a rail base flange, and an inward projection within each hook adapted to engage the under surface of a rail base flange at a location nearer the flange edge than the location of engagement by the hook tip.

11. A rail anchor comprising a body and a hook at each end of the body, each hook being formed at its tip end to engage with either the upper or the under surface of a rail base flange, the body of the anchor being formed at each end, within the hooks, to engage the under surface of a rail base flange at a location nearer the flange edge than the location of engagement by the hook tip.

12. A rail anchor comprising a body and a hook at each end of the body, each hook being formed at its tip end to engage the

upper surface of a rail base flange, the body of the anchor being formed at each end, within the hooks, to have a single area of engagement with the under surface of a rail base flange, relatively short in the direction of flange width.

13. A rail anchor comprising a body and a hook at each end of the body, each hook being formed at its tip end to engage the upper surface of a rail base flange, the body of the anchor being formed at each end, within the hooks, to have a single area of engagement with the under surface of a rail base flange, relatively short in the direction of flange width, said area being disposed nearer the flange edge than the location of engagement by the hook tip.

14. A rail anchor comprising a body and a hook at each end of the body, each hook being formed at its tip end to engage the upper surface of a rail base flange and being further formed at its tip end to engage the under and edge surfaces of a rail base flange, the body of the anchor being formed at each end, within the hooks, to engage the under surface of a rail base flange.

15. A rail anchor comprising a body and a hook at each end of the body, each hook being formed at its tip end to engage the upper surface of a rail base flange and being further formed at its tip end to engage the under and edge surfaces of a rail base flange, the body of the anchor being formed at each end, within the hooks, to engage the under surface of a rail base flange at a location nearer the flange edge than the location of engagement by the hook tip.

16. A rail anchor comprising a body and a hook at each end of the body, each hook being formed at its tip end to engage the upper surface of a rail base flange and being further formed at its tip end to engage the under and edge surfaces of a rail base flange, the body of the anchor being formed at each end, within the hooks, to have a single area of engagement with the under surface of a rail base flange, relatively short in the direction of flange width.

17. A rail anchor comprising a body and a hook at each end of the body, each hook being formed at its tip end to engage the upper surface of a rail base flange and being further formed at its tip end to engage the under and edge surfaces of a rail base flange, the body of the anchor being formed at each end, within the hooks, to have a single area of engagement with the under surface of a rail base flange, relatively short in the direction of flange width, said area being disposed nearer the flange edge than the location of engagement by the hook tip.

18. A one-piece rail anchor including a hook at one end to embrace one flange of a rail base and a hook at the other end adapted at the outer side of its tip end to thrust

upwardly against the other flange of a rail base.

19. A one-piece rail anchor including a hook at each end adapted to embrace one flange of a rail base, and each further adapted at the outer surface of its tip for abutting engagement with the edge and under surfaces of one flange of a rail base when the other end is in embracing engagement with the other flange.

20. A one-piece rail anchor including a pair of substantially similar hooks disposed one at each end of the anchor and both on the same side of the anchor and each adapted to embrace one flange of a rail base, the anchor being further adapted at each end on the outside of the hooks for abutting engagement with the edge surface of one flange of a rail base when the other end is in embracing engagement with the other flange.

21. A rail anchor including a shank and substantially similar hooks at opposite ends thereof, the shank and hooks lying in the same plane and the shank being bent.

22. A rail anchor including a shank and substantially similar hooks, one at each end thereof, each adapted at its tip end to engage a rail base flange in either of two ways.

23. A rail anchor including a shank and substantially similar mutually facing hooks one at each end thereof formed on the same side of the shank, the shank and hooks lying in the same plane and the shank being bent.

24. A rail anchor including a shank bent at each end to provide an offset portion for engagement with the under side of a rail base and a hook at each end of the shank overlying the offset portion of the shank.

25. A rail anchor including a shank bent at each end to provide an offset portion for engagement with the under side of a rail base and further bent between said offset portions, and a hook at each end of the shank overlying the offset portion of the shank.

26. A rail anchor including a body and a hook at each end thereof for engagement severally with the flanges of a rail base, the anchor being formed to locate the hooks in such relation to a rail that in service one hook will be subjected to stress tending to open the same while the other hook will be subjected to stress tending to close the same.

27. A rail anchor including a body and a hook at each end thereof for engagement severally with the flanges of a rail base, the anchor being formed to locate the hooks in such relation to a rail that in service one hook will be subjected to stress tending to open the same while the other hook will be subjected to stress tending to close the same, the hooks being substantially similar and each capable of engaging a rail in either of two positions, one of such positions entailing closing stress and the other position entailing opening stress.

tailing opening stress, whereby the anchor may be reversed in its relation to a rail to thereby reverse the stresses in the hooks.

28. A rail anchor including a body and a hook at each end thereof adapted for forcible application singly to a rail base flange to grippingly embrace the flange and to be thereby subjected to stress tending to open such hook, said hooks being further adapted for forcible application singly to abut a rail base flange and to be thereby subjected to stress tending to close such hook, the similar formation of the hooks enabling the anchor to be reversed in its relation to a rail thereby to reverse the stresses in the hooks.

29. A rail anchor adapted to grippingly embrace a rail base transversely thereof and including hooks at the ends each hook being adapted to grippingly embrace one flange of a rail base while the other hook at its tip end grippingly abuts the other flange of the rail base, the capacity of the hooks to each function in either of the two relations to a rail rendering the anchor reversible.

30. A rail anchor including a body and a pair of substantially similar hooks, one at each end of the body and adapted for engagement severally with the flanges of a rail base, the anchor being formed to dispose the hooks in such normal relations to the rail that stresses then imposed tend to open one hook and to close the other hook.

31. A rail anchor including a body and a pair of substantially similar hooks, one at each end of the body and on the same side thereof, adapted to assume different relations to a rail to which the anchor is applied.

32. A rail anchor including a shank and a pair of hooks, one at each end thereof, each hook being formed internally and externally at its tip for engagement with a rail base flange.

33. A rail anchor including a shank and a pair of hooks, one at each end thereof, each hook being formed internally at its tip and back and externally at its tip for engagement with a rail base flange.

34. In a rail anchor, a body and substantially similar hooks at the ends thereof and on the same side thereof adapted when in operation one to embrace one flange of a rail base and the other to be disposed below the other flange to thrust against a tie, the force of said thrust being transmitted from the lower to the upper hook as simultaneous flexion and torsion stresses in the body.

35. A rail anchor including a shank and a hook at each end of the shank adapted to contractingly embrace a rail base flange, the anchor being provided at each end on the tip of the hook with a shoulder to abuttingly engage the edge surface of a rail base flange opposite the embraced flange, each hook being formed to bear upon the upper and lower

surfaces of an embraced flange at locations so differently spaced from the flange edge that the contractile action of the flange embracing hook upon a flange will urge the anchor to movement such as will engage the shoulder at the opposite end with a flange edge and will maintain the engagement so established.

36. An anchor comprising a body and a pair of hooks, one at each end of the body, each of said hooks being adapted to embracingly engage one flange of a rail base and at another time to be disposed tip uppermost entirely below the upper surface of the rail base in position to thrust against a tie.

37. An anchor comprising a body and a pair of hooks, one at each end of the body, each of said hooks being adapted to embracingly engage one flange of a rail base and at another time to be disposed beneath the rail base in position to thrust against a tie, each of said hooks being formed at the outer surface of its tip to abuttingly engage the edge surface of a flange when the hook is in tie engaging position to hold the other hook in operative flange embracing relation to a rail.

38. An anchor comprising a body and a pair of hooks, one at each end thereof formed on the same side of the body, each of said hooks being adapted to embracingly engage one flange of a rail base and at another time to be disposed beneath the rail base in position to thrust against a tie, each of said hooks being provided with means to abuttingly engage the edge surface of a flange when the hook is in tie engaging position to hold the other hook in operative flange embracing relation to a rail, and each of said hooks being formed to bear upon the upper and lower surfaces of a flange embraced by it at locations so differently spaced from the flange edge that contractile action

of the hook upon the flange will urge the anchor to movement such as will engage the shoulder at the opposite end with the adjacent flanged edge and will maintain the engagement so established.

39. A one-piece rail anchor comprising a shank and a pair of substantially similar hooks located one at each end thereof and each adapted to embrace one flange of a rail base thereby to dispose the other hook beneath the other flange and to incline the shank relatively to the rail base.

40. A one-piece rail anchor comprising a shank and a pair of substantially similar hooks located one at each end thereof and on the same side of the shank each including a shoulder to engage the edge surface of a rail base flange and each adapted to embrace one flange of a rail base thereby to dispose the other hook beneath the other flange and to locate the shoulder thereof in engagement with a flange edge.

41. A rail anchor adapted to grippingly embrace a rail base transversely thereof and including hooks at the ends formed on the same side of the anchor, each hook being adapted to grippingly embrace one flange of a rail base while the other hook grippingly abuts the other flange of the rail base, the capacity of the hooks to each function in either of the two relations to a rail rendering the anchor reversible.

42. A rail anchor comprising a bar of metal bent toward its ends to form a pair of substantially similar U-shaped hooks each designed to receive a rail base flange between its tip and the bar adjacent the hook bend, said hooks being disposed both on the same side of said bar and with their open ends mutually facing.

43. A rail anchor comprising a bar of metal bent toward its ends to form a pair of substantially similar U-shaped hooks disposed both on the same side of said bar and with their open ends mutually facing, the bar being bent between the hooks in the plane of the hooks.

44. A rail anchor comprising a bar of metal bent toward its ends to form a pair of substantially similar U-shaped hooks disposed both on the same side of said bar and with their open ends mutually facing, said bar being further formed to provide a shoulder on the outside of each hook.

45. A rail anchor comprising a bar of metal including a central portion and end portions both reversely bent to form a pair of substantially similar hooks disposed both on the same side of the bar.

46. A rail anchor comprising a bar of metal bent toward its ends to rail flange embracing form at each end and constituting similar hooks located both on the same side of the bar.

47. A rail anchor comprising a bar of metal bent toward its ends to rail flange embracing form, thereby constituting similar hooks located both on the same side of the bar, said bar being shouldered on the outside of each bent portion or hook, thereby constituting rail flange abutments.

48. A rail anchor comprising a bar of metal bent toward its ends to form hooks capable of grippingly embracing a rail flange and shoulders formed on the outsides of the hooks in such relation to the hooks that gripping engagement of a hook with one flange of a rail base will cause gripping engagement of the shoulder at the opposite end of the anchor with the edge of the other flange.

49. A rail anchor comprising an intermediate portion to extend under a rail base and substantially similar hook portions disposed at opposite ends of the intermediate portion on the same side thereof, the an-

chor being designed at either end to embrace a rail base flange between the hook portion and the intermediate portion.

50. A rail anchor adapted to grippingly embrace a rail base transversely thereof, including similar yieldable means at the ends thereof adapted to engage the rail base flanges and to be thereby subjected to dissimilar stresses during operative relation of the anchor and rail.

51. A rail anchor adapted to grippingly embrace a rail base including a hook at one end adapted to forcibly bear upon the upper and lower surfaces of a base flange at locations spaced inwardly from the edge of the flange, and yieldable means at the other end to abuttingly engage the edge of the other base flange.

52. A rail anchor adapted to grippingly embrace a rail base transversely thereof including hooks at the ends, either of which is adapted to forcibly bear upon the upper and lower surfaces of a base flange at locations spaced inwardly from the edge of the flange, while the tip of the other hook is in abutment with the other flange of the rail base.

53. A rail anchor adapted to grippingly embrace a rail base transversely thereof including hooks at the ends, either of which is adapted to forcibly bear on the upper and lower surfaces of a base flange at locations spaced inwardly from the edge of the flange, the embraced flange being out of engagement at and near its edge with the embracing hook, while the tip of the other hook is in base gripping abutment with the edge of the other flange.

54. A rail anchor adapted to grippingly engage a rail base transversely thereof including a body and a hook at each end thereof located both on the same side of the body and either adapted to forcibly bear upon the upper and lower surfaces of a rail base flange at locations spaced inwardly from the edge of the flange while the other hook is in base gripping abutment with the edge of the opposite flange.

55. A rail anchor adapted to grippingly embrace a rail base transversely thereof including a hook at one end adapted to forcibly bear upon the upper and lower surfaces of one flange of a rail base at locations spaced inwardly from the edge thereof and to a different extent, whereby pressure exerted through the hook upon the said flange tending to its distortion is applied to the flange at locations where its resistance to distortion is greater than at the edge, and yieldable means at the other end grippingly abutting the edge of the other flange.

In witness whereof, I have hereunto set my hand.

FRANCIS W. COOPER.
